PROTECTIVE WORK CHAMBER

Frederick John May, Wantage, England

Filed Sept. 25, 1963, Ser. No. 76,721

Term of patent 14 years

(Cl. D16—2)

FIG. 1.

FIG. 4.

FIG.2.

FIG.3.

FIGURE 1 is a perspective view of a protective work chamber, embodying my new design.

FIGURE 2 is a side elevation as seen from the left of FIGURE 1; and

FIGURE 3 is a bottom plan view thereof.

FIGURE 4 is a rear elevation thereof.

I claim:

The ornamental design for a protective work chamber, as shown.
